Primary Examiner — Katherine Glennon

(74) Attorney, Agent, or Firm — Rathe Lindenbaum LLP

(57) **CLAIM**

I claim the ornamental design for a computer, as shown and described.

DESCRIPTION

FIG. 1 is a rear perspective view of the claimed design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines formed by dashes show unclaimed subject matter and form no part of the claimed design.

1 Claim, 5 Drawing Sheets
